UNITED STATES PATENT OFFICE.

JACOB SUTTER, OF NEW YORK, N. Y.

DESIGN FOR A JAR-CLOSURE.

48,994.

Specification for Design.

Patented May 2, 1916.

Application filed February 16, 1916. Serial No. 78,771. Term of patent 7 years.

To all whom it may concern:

Be it known that I, JACOB SUTTER, a subject of the Czar of Russia, residing at New York, in the county of New York and State of New York, have invented a new, original, and ornamental Design for Jar-Closures, of which the following is a specification, reference being had to the accompanying drawing, forming a part thereof.

The figure is a perspective view of a jar closure, showing my new design.

I claim:

The ornamental design for a jar closure, as shown.

JACOB SUTTER.
